DESIGN FOR A STAMPING MACHINE

Olaf Halvorsen, Jacksonville, Fla.

Application December 8, 1947, Serial No. 143,037

Term of patent 7 years

(Cl. D63—1)

To all whom it may concern:

Be it known that I, Olaf Halvorsen, a citizen of the United States, residing at Jacksonville, in the county of Duval and State of Florida, have invented a new, original, and ornamental Design for a Stamping Machine, of which the following is a specification, reference being had to the accompanying drawing, forming a part thereof.

Figure 1 is a side elevation of a stamping machine embodying my new design.

Figure 2 is a front elevation thereof with the stamping head omitted for convenience of illustration;

Figure 3 is a top plan view thereof.

The dominant features of my design reside in the portions shown in full lines.

I claim:

The ornamental design for a stamping machine, as shown and described.

OLAF HALVORSEN.
